Primary Examiner — Karen S Acker

(57) **CLAIM**

The ornamental design for electric vegetable slicer, as shown and described.

DESCRIPTION

1. Electric vegetable slicer

1.1 : Perspective

1.2 : Front

1.3: Right

1.4 : Left

1.5: Back

1.6: Top

1.7: Bottom

The broken lines illustrate portions of the electric vegetable slicer that form no part of the claimed design.
